UNITED STATES PATENT OFFICE

FRANCESCO GULIA AND ADDISON S. SNELL, OF OKMULGEE, OKLAHOMA

CASHIER PROTECTOR

Application filed July 13, 1931. Serial No. 550,534.

This invention relates to bank cages of that type in which manually operated means releases a shutter which flies up and covers the front of the cage above the counter and thus protects the occupant of the cage from gun fire and from being held up by burglars.

An object of the invention is to provide novel loop leaf springs which are normally compressed and, when released, exert a balanced force against the bottom of the shutter to slide the shutter instantly upward with accuracy so that buckling and binding of the shutter in the emergency will positively be prevented and instant response be assured when the shutter releasing means is manually actuated.

A further object is to provide releasing means for the shutter comprising a treadle and a spring-pressed catch, which latter holds the shutter at its lower limit of movement in inoperative position against the tension of the loop leaf springs, the treadle being pivoted and being disposed within convenient reach of the cage occupant's foot so as to be readily accessible in times of emergency while, at other times, being out of the way so as not to be accidentally struck.

A still further object is to provide an alarm device including a push button and an electric bell or other audible signal, the push button being located in the path of movement of a projection carried near one lower corner of the shutter so that, as the shutter travels upward, the alarm device will be sounded when the shutter reaches nearly its upper limit of movement.

A still further object is to provide a device of this character which will be formed of a few strong and durable parts which will be inconspicuous and concealed when assembled with the cage and which will not easily get out of order.

With the above and other objects in view the invention consists in certain novel details of construction and combinations of parts hereinafter fully described and claimed it being understood that various modifications may be resorted to within the scope of the appended claims without departing from

the spirit or sacrificing any of the advantages of the invention.

In the accompanying drawings forming part of this specification,

Fig. 1 is a rear elevation of a bank cage 55 equipped with the invention,

Fig. 2 is a view similar to Fig. 1 but showing the device in operative position to close the grid above the counter,

Fig. 3 is a vertical sectional view taken on 60 the line 3-3 of Fig. 1,

Fig. 4 is a cross sectional view taken on the line 4-4 of Fig. 1,

Fig. 5 is a detail longitudinal sectional view showing the push button and actuating 65 projection therefor on the shutter,

Fig. 6 is a fragmentary detail elevation showing the bottom pivot of one of the loop leaf springs,

Fig. 7 is a detail sectional view showing 70 the top pivot of one of the loop leaf springs, and

Fig. 8 is a diagrammatic view showing the electric circuit wiring for the audible alarm.

Referring now to the drawings in which like characters of reference designate similar parts in the various views, 10 designates a bank cage provided with the usual grid 11 above the counter 12, which latter, as usual, extends beyond both the front and back of 80

In carrying out the invention, we slidably mount a substantially rectangular metal shutter 13 on the vertical side posts 14 of the cage, the shutter being concealed from the front by the usual panel 15 below the counter, as best shown in Fig. 3. As best shown in Fig. 4, the shutter is guided in its vertical movement by angle iron guides 16 which embrace the side edges of the shutter and are secured to the posts 14. The shutter is preferably formed of sufficient size to form a closure in front of the grid 11 when at its upper limit of movement and protect the occupant of the cage from gun fire.

For operating the shutter, we provide a pair of loop leaf springs 17 and 18 disposed on opposite sides of the shutter and crossing each other at spaced points 19 in parallel planes. Each spring is pivoted at the bottom

to the floor sill 20 of the cage preferably by means of a hinge 21, best shown in Fig. 6, the leaves of which may be bolted, riveted, or otherwise secured to the leaf spring and to the sill. The top of each spring is likewise pivoted to the shutter 13 near the bottom thereof by means of a pivot pin 22, best shown in Fig. 7, around which the end of the spring is preferably looped and riveted, the pivot pin being assembled with a base plate 23 which is riveted or otherwise rigidly secured to the metal shutter.

By referring now to Figs. 1 and 2, it will be seen that the ends of each loop leaf spring are pivotally secured in vertical alinement near the extreme lateral ends of the floor sill and the shutter, and that both loop leaf springs cross each other at spaced points 19 disposed approximately coincident with the longitudinal center line of the shutter. By virtue of this construction, the pressure of the springs during expansion will be equalized or balanced on the shutter so that the shutter will be instantly and truly slid upwardly in the guides 16 without danger of buckling or binding therein while the tension springs are expanding.

For normally holding the shutter at its lowest limit of movement against the tension of the loop leaf springs, a pin 24, best shown in Figs. 3 and 4, is mounted to slide toward and away from the rear face of the shutter through the legs of a substantially U-shaped bracket 25 which is rigidly secured in any preferred manner to the sill 20 midway between the ends thereof. A cleat 26 is secured to the shutter near the center of the bottom edge thereof and, during downward movement of the shutter, the cleat rides over a bevel formed on the end of the pin 24 and presses the pin back against the tension of a helical spring 27 which surrounds the pin between the legs of the bracket and is confined between one of said legs and a pin 28 passed through the pin 24, as best shown in Fig. 4. The spring urges the pin 24 back over the cleat when the cleat has passed downwardly therebeyond and automatically locks the shutter at its lowest limit of movement in inoperative or released position.

For withdrawing the pin 24 from engagement with the cleat, we provide a treadle comprising a rock shaft 29 which extends longitudinally of the floor sill and is rotatably mounted at the ends in angle irons 30 rigidly secured to the sill. A rod pedal 31 extends parallel with the shaft, and the ends thereof are bent abruptly toward the shaft and rigidly secured to the ends of the shaft preferably outside of the bearings 30, as best shown in Fig. 4. The pedal and shaft are of sufficient length to extend throughout the entire width of the cage so as to be easily and quickly as well as naturally accessible to the occupant of the cage by simply step-

ping forward with either foot to depress the pedal 31. A crank lever 32, best shown in Fig. 3, is fixed to the center of the rock shaft in any preferred manner and is terminally pivoted to the outer end of the release pin 24. It is now clear that when the pedal 31 is depressed, the rock shaft 29 will be rotated toward the operator, and, through the instrumentality of the crank lever 32, will withdraw the pin 24 against the tension of its controlling spring and release the shutter, which immediately is shot upwardly by the tension of the loop springs 17 and 18 to seal the grid.

In the inoperative position illustrated in Fig. 1, the shutter is entirely concealed below the counter and behind the front panel 15 and, in this position, the strong loop leaf springs are under great tension and the shutter is held by the pin 24 engaging the cleat 26. On desiring to throw the shutter into operative position, it is only necessary for the occupant of the cage to step on the pedal 31, which, through the medium of the lever 32, will actuate the pin 24 and disengage it from the cleat, thus allowing the shutter to be pushed up instantly under the influence of the force exerted by the expansion of the strong pair of loop leaf springs.

It is desirable that an alarm be sounded at the instant the shutter is being closed, and, for the purpose, preferably we mount an audible alarm device, such as an electric bell 33, at any convenient location, such as, for instance, near one of the side posts of the cage, as best shown in Figs. 1 and 2. Preferably, a switch 34 of the push button type is mounted in any preferred manner on one of the side posts 14 on the inner side thereof, just below the counter 12, and is spaced from the post in any preferred manner, such as, for instance, by means of a bracket arm 35 secured to the post. A projection 36, best shown in Fig. 5, is secured to the inner face of the shutter near the corner thereof and directly in line with the button of the push button switch so that, as the shutter nears its upper limit of movement when traveling upwardly, the projection will have wiping contact with said button and close the switch. To facilitate accurate working of the parts, the projection 36 is preferably in the form of an arched strap, both ends of which are obliquely inclined to provide cams 37 which ride freely over the button of the push button switch when moving past the latter in either direction.

As best shown in Fig. 8, the switch 34 and bell 33 are connected in series with any source of electrical current supply, such as, for instance, a storage battery 38, by means of suitable conductor wires 39 and 40.

It is now clear that when the shutter is moving upwardly, just before it reaches its top limit of movement, the projection 36 will

impinge against the button of the switch and close the circuit through the bell so that the alarm is sounded and will continue to be sounded while the shutter remains closed, 5 that is, at its top limit of movement.

From the above description, it will be seen that we have provided a simple and effective bank cage which will protect the occupant from being held up or shot at from persons 10 outside the cage and which can be operated instantly, and which, in operation, will work with great accuracy due to the balanced pressure of the controlling loop leaf springs against the shutter.

15 It will be observed by referring to Figs. 1 and 2 that a pair of stop lugs 41 are provided to project forwardly from the shutter and impinge against a transverse abutment bar 42 below the counter and limit upward 20 movement of the shutter.

While we have described and illustrated the invention as being fabricated with a bank cage, it will be understood that the shutter, alarm, springs, etc., may be equally well applied wherever the need for protection arises. 25

Having thus described the invention, we claim:

1. In an operating device for slidable shutters, loop leaf springs for throwing the shutter to closed position, said loop leaf springs being adapted to be disposed on opposite sides of the shutter and cross each other at spaced points in parallel planes, means for pivotally securing the ends of the springs respectively 35 to the shutter and to a rigid support, and means for normally holding the springs tensioned against the shutter at its open limit of movement in retracted position, the ends of each spring being disposed near each other 40 when the shutter is retracted and each spring being adapted to expand into substantially V-shape when the shutter is closed.

2. In an operating device for slidable shutters, loop leaf springs for throwing the shutter to closed position, said loop leaf springs being adapted to be disposed on opposite sides of the shutter and cross each other at spaced points approximately at the center line of the shutter, means for pivotally connecting one end of each spring to the shutter near an end of the shutter, means for pivotally connecting the opposite end of each spring to a rigid support, both of said means being disposed substantially in alignment 50 with each other, and means for normally holding the springs tensioned against the shutter when the shutter is open in retracted position, the ends of each spring being disposed near each other when the shutter is retracted and each spring being adapted to expand into substantially V-shape when the shutter is closed.

3. In an operating device for slidable shutters, guides for directing sliding movement 55 of the shutter, loop leaf springs for throwing

the shutter to closed position, said loop leaf springs being adapted to be disposed on opposite sides of the shutter and cross each other at spaced points substantially midway between the guides, means for securing the ends 70 of the loop leaf springs respectively to the shutter and to a stationary support, and means for normally holding the springs tensioned against the shutter when the shutter is open in retracted position, the ends of each 75 spring being disposed near each other when the shutter is retracted and each spring being adapted to expand into substantially V-shape when the shutter is closed.

4. In an operating device for slidable shutters, loop leaf springs for throwing the shutter to closed position, said loop springs being adapted to be disposed on opposite sides of the shutter and cross each other at spaced points substantially at the center line of the 80 shutter, means for securing the ends of the springs respectively to the shutter and to a stationary support, a cleat adapted to be disposed on the shutter, a spring-pressed release pin adapted to be disposed on said support 85 and normally engaged over said cleat for holding the shutter open in retracted position and holding the springs tensioned against the shutter, and means operatively connected to said pin for withdrawing the pin from the 90 cleat to permit said springs to expand and close the shutter, the ends of each spring being disposed near each other when the shutter is retracted and each spring being adapted to expand in substantially V-shape when the 95 shutter is closed.

In testimony whereof we affix our signatures.

FRANCESCO GULIA.
